(57) **CLAIM**

The ornamental design for a foldable front cover for electronic tablet, as shown and described.

DESCRIPTION

FIG. 1 shows a perspective view for a design of a foldable front cover for electronic tablet.

FIG. 2 shows a top view of the front cover.

FIG. 3 shows a top view of an exterior of the front cover and case.

FIG. 4 shows a bottom view of an interior of the front cover and case.

FIG. 5 shows a left side view of the front cover and case.

FIG. 6 shows a right side view of the front cover and case.

FIG. 7 shows a perspective view of the front cover folded into a stand to provide a first angle for the electronic tablet; and, FIG. 8 shows a perspective view of the front cover folded into a stand to provide a second angle for the electronic tablet. The broken-line features in the figures are for illustrative purposes only and form no part of the claimed design.
